UNITED STATES PATENT OFFICE

LEWIS W. FRANKS, OF PORT NECHES, TEXAS

CLOSURE HANGER

Application filed June 22, 1928. Serial No. 287,608.

This invention relates to sliding closures, and aims to provide a novel form of hanger whereby a sliding closure may be readily and easily operated and one which will move vertically out of engagement with the floor or carpet directly thereunder, eliminating wear on the carpet and permitting the closure to be moved with facility.

Another object of the invention is to provide a closure which will move into the wall adjacent to the closure opening when the closure is in its inactive position, with the result that the closure will not take up space in the room.

A still further object of the invention is the provision of a latch mechanism which will operate automatically to lock the closure in its closed position.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view illustrating a closure constructed in accordance with the invention, as in its open position.

Figure 2 is a sectional view taken on line 2—2 of Figure 1.

Figure 3 is an elevational view similar to Figure 1, and showing the closure in its closed position.

Figure 4 is an elevational view of a sliding closure in its closed position.

Referring to the drawing in detail, the reference character 5 designates a door opening, the door frame at one side of the opening being open to allow the door to slide thereto, when the door is moved to its open position.

The closure is indicated generally by the reference character 6 and embodies a frame formed of vertical parallel bars 7 and 8 respectively, connected at their upper ends by means of the bar 9, which as shown is sub-

stantially long, one end thereof extending an appreciable distance beyond one edge of the door so that it will contact with the beam 10, forming a part of the frame of the building, to restrict the movement of the closure.

At the lower ends of the bars 7 and 8 is a bar 11 which holds the lower ends of the bars 7 and 8 in their proper spaced relation with each other. Secured to the side faces of the frame of the closure are boards 12, between which the main hanger 13 and latch mechanism, to be hereinafter more fully described, is supported.

The main hanger 13 comprises a bar pivotally supported at its lower end on the floor of the room in which the closure is positioned, the pivotal connection between the hanger 13 and floor being made through the bracket 14. This hanger is substantially long as compared with the length of the closure, the upper end of the hanger being pivotally connected to the bar 9, at 15 with the result that when the closure is slid laterally, it will be elevated so that the lower edge thereof will not contact with the floor as it is being moved.

Cooperating with the hanger 13, is a hanger 16 which is of a length equal to the length of the hanger 13, the hanger 16 being connected to the extension of the bar 9, at 17, while the lower end of the hanger 16 is pivotally connected to the floor at 18. The hanger 16 acts to balance the closure to insure the true operation thereof.

The reference character 19 designates a coiled spring that has one end connected to the bar 8, while the opposite end thereof is connected with the hanger 13 so that when the closure is moved to its open position as shown by figure 1 of the drawings, the spring 19 will be placed under tension to hold the closure in its open position.

The reference character 20 designates a coiled spring that has connection with the bolt 21 extending through the bar 7, the opposite end of the spring 20 being connected with the hanger 13 so that when the closure is moved to a position as shown by Figure 3 of the drawings the spring 20 is placed under tension to hold the closure in its closed position.

5 A latch indicated at 22 and which is in the form of a pivoted arm, is secured to the bar 7 of the closure frame, at 23, the arm being indicated by the reference character 22. A notch 24 is formed in the arm 22 and is adapted to fit over the pin 25 extending laterally from the hanger 13 to lock the closure in its closed position.

10 A spring 26 engages the upper edge of the arm 22 and normally urges the arm 22 downwardly so that locking of the closure will be insured. To further lock the arm 22, a rotary locking member 27 is provided, the same being key controlled so that it may be locked in contact with the upper edge of the arm 22 to prevent movement of the arm 22 by unauthorized persons.

15 Secured to the inner end of the arm 22 is an operating shaft 28 that extends through the closure so that it may be conveniently grasped by the operator and slightly rotated to lift the arm 22 against the action of the spring 26 to release it from the pin 25, when it is desired to move the closure to its open or inactive position.

20 26 From the foregoing it will be obvious that while I have shown and described the invention for use as a sliding closure such as a door, the construction and operation of the device is such that it may be used in the construction of shutters, or any sliding closure wherein it is desired to provide a closure which will be concealed when in its open position.

What is claimed is:—

35 30 In a device of the class described, a closure, said closure including an upper bar of a length to extend an appreciable distance beyond one edge of the closure, a pair of pivoted hangers, one of the hangers having pivotal connection with the upper bar at a point adjacent to the free end thereof, and the opposite hanger being pivotally supported at a point laterally of the closure and having its upper end pivotally connected with the closure at a point intermediate the side edges of the closure.

40 45 In testimony that I claim the foregoing as my own, I have hereto affixed my signature.

LEWIS W. FRANKS.
